(57) **CLAIM**

The ornamental design for a solar battery module, as shown and described.

DESCRIPTION

FIG. 1 is a front elevational view of a solar battery module showing a first embodiment of our new design.

FIG. 2 is an enlarged partial front elevational view thereof, taken along line 2-2 of FIG. 1.

FIG. 3 is an enlarged partial front elevational view thereof, taken along line 3-3 of FIG. 1.

FIG. 4 is an enlarged partial front elevational view thereof, taken along line 4-4 of FIG. 1.

FIG. 5 is an enlarged partial front elevational view thereof, taken along line 5-5 of FIG. 1.

FIG. 6 is a rear elevational view thereof.

FIG. 7 is a right side elevational view thereof, the left side elevational view being a mirror image thereof.

FIG. 8 is a top plan view thereof.

FIG. 9 is an enlarged view of the 9-9 portion in FIG. 1.

FIG. 10 is a front elevational view of a solar battery module showing a second embodiment of our new design.

FIG. 11 is an enlarged partial front elevational view thereof, taken along line 11-11 of FIG. 10.

FIG. 12 is an enlarged partial front elevational view thereof, taken along line 12-12 of FIG. 10.

FIG. 13 is an enlarged partial front elevational view thereof, taken along line 13-13 of FIG. 10.

FIG. 14 is an enlarged partial front elevational view thereof, taken along line 14-14 of FIG. 10.

(Continued)

FIG. 15 is a rear elevational view thereof.
 FIG. 16 is a right side elevational view thereof, the left side elevational view being a mirror image thereof.
 FIG. 17 is a top plan view thereof; and,
 FIG. 18 is an enlarged view of the 18-18 portion in FIG. 10. The evenly-spaced broken lines show unclaimed environmental structure. The dash-dot-dash broken lines is included to show boundaries that form no part of the claimed design. All broken line portions of the figure drawings form no part of the claimed design.
